UNITED STATES PATENT OFFICE.

PAUL J. MURRAY, OF OSWEGO, NEW YORK.

DEVICE FOR DETECTING AND COOLING HOT JOURNALS.

1,228,231.

Specification of Letters Patent.

Patented May 29, 1917.

Application filed August 11, 1916. Serial No. 114,489.

To all whom it may concern:

Be it known that I, PAUL J. MURRAY, a citizen of the United States, residing at Oswego, in the county of Oswego, State 5 of New York, have invented a new and useful Device for Detecting and Cooling Hot Journals; and I do hereby declare the following to be a full, clear, and exact description of the invention, such as 10 will enable others skilled in the art to which it appertains to make and use the same.

The present invention relates to a device for detecting and cooling hot journals 15 on railway trains, the object of the invention being to provide a device of this character which embodies novel features of construction whereby air will be automatically supplied to a hot journal for the purpose 20 of cooling the same, the air brakes being simultaneously applied if the journal is sufficiently hot to require immediate attention.

Further objects of the invention are to 25 provide a device of this character which is comparatively simple and inexpensive in its construction, which can be used in connection with the conventional air brake systems, which is entirely automatic in its 30 operation, and which will either supply a small amount of air for cooling a slightly 35 hot journal without stopping the train, or supply a larger amount of air and simultaneously apply the air brakes if the journal is sufficiently hot to need prompt attention.

With these and other objects in view, the 40 invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a side elevation of one end 45 of a railway car having the improved device for detecting and cooling hot journals mounted upon the truck thereof.

Fig. 2 is a perspective view showing the 50 device as detached from the truck.

Fig. 3 is an enlarged sectional view

through the end of one of the air pipes and the fuse cap thereon.

Fig. 4 is a similar view showing a slight 55 modification.

Fig. 5 is a detail view showing a further modification of the invention.

Corresponding and like parts are referred to in the following description and indicated in all the views of the drawings by 60 the same reference characters.

For the purpose of illustration the invention is shown as applied to the truck A of a car B, said car being equipped with the conventional air brake system, of which 65 the numeral 1 designates the air pipe. The end of the car is shown as provided with the usual coupling 2 and air hose 3. Extending transversely across the top of the truck A at a point between the wheels is a 70 pipe 4, the middle of the pipe being shown as provided with a T-connection 5 which engages a nipple 6 at one end of a flexible 75 hose 7, the opposite end of the flexible hose being provided with a nipple 8 which engages a T-connection 9 interposed in the air brake pipe 1. The nipples 6 and 8 preferably have right and left threads, respectively, so that there is no difficulty in placing the flexible hose 7 in position, or 80 removing it therefrom. The ends of the transverse pipe 4 communicate with longitudinally extending pipes 10, the ends of the said pipes 10 entering the journal boxes 11. Fuse caps 12 are removably fitted upon 85 the extremities of the pipes 10, each of said fuse caps being provided with a small aperture 13 and a large aperture 14. The small apertures 13 are closed by fuses 15 having a composition which will melt at a comparatively low temperature, while the large 90 apertures 14 are closed by fuses 16 having a composition which will melt at a higher temperature.

If one of the journals begins to get warm, 95 the fuse 15 of the small aperture 13 will melt and allow a slight flow of air to play upon the journal, thereby cooling it or tending to prevent it from getting so hot as to necessitate stopping the train before reaching a regular stopping place. However, if 100 one of the journal boxes gets so hot as to

require prompt attention, the fuse 16 of the large aperture 14 will melt, thereby supplying a larger quantity of air to the journal, and at the same time exhausting the air 5 from the air brake system to such an extent as to cause a gradual application of the regular air brakes. The train is thus brought to a stop, and the hot journal can be easily detected by the hissing sound 10 caused by the escaping air. The air will cool the journal, after which a new fuse is applied and the journal box repacked. The train can then proceed upon its way.

A slight modification is shown by Fig. 15 4, in which the cap 12 is provided with whistle members 17 located respectively over the apertures 13 and 14. These whistles have a different construction so as to give 20 different sounds, and when one of the fuses is melted, the escaping air will sound the whistle. This is not at all essential, although it may, under some circumstances, be of assistance in locating the hot journal. Where the journal is only slightly heated 25 and only the fuse 15 of the small aperture 13 melts, the train can proceed without delay to a regular stopping place, whereupon the journal can be repacked and properly attended to.

30 A further slight modification is shown by Fig. 5, in which the heavier fuse 16^a is provided with a central opening within which the lighter fuse 15^a is fitted. It may be convenient to assemble the fuses in this manner, and the heavier fuse could be constructed to be threaded into the cap 12, or otherwise fitted to the same. It would probably be preferable to have the fuses fitted 35 in extra caps at the shops, so that in order to replace a blown fuse it would be merely necessary to remove the cap 12 and substitute a new cap. It will, of course, be understood that the pipes can be carried on the inside of the truck, as well as upon 40 the outside of the truck, since the manner of mounting the pipes upon the truck is quite immaterial to the invention. The heavy fuse and the light fuse are different in size, so that there is no possibility of one 45 being confused with the other, and two of the light fuses or two of the heavy fuses 50 used by mistake.

Having thus described the invention, what I claim as new and desire to secure by Letters Patent, is:—

1. The combination with a railway car, including its truck and air brake systems, of pipes leading from the air brake pipe to the journal boxes of the truck, and fuse 60 means closing the ends of the pipes and constructed to permit a small quantity of air to escape and play upon the journals when the journals become only slightly heated, the amount of the escaping air be-

ing insufficient to cause an application of the brakes.

2. The combination with a railway car including its truck and air-brake system, of pipes leading from the air brake pipe to the journal boxes of the truck, fuse caps arranged within the journal boxes and applied to the ends of the pipes, said fuse caps being each provided with a small aperture and a large aperture, and fuses closing the apertures, the fuse of the small aperture 75 being of a composition which will melt at a lower temperature than that of the large aperture so that if the journal is only slightly heated the small aperture will be opened, while if the journal is hot the large 80 aperture will also be opened, thereby exhausting the air from the air-brake system and causing the air-brakes to be applied, the escaping air in either instance serving 85 to cool the journal.

3. The combination with a railway car including its truck and air brake system, of pipes leading from the air brake pipe to the journal boxes of the truck, and fuse means normally closing the ends of the pipes 90 and constructed to permit a small quantity of air to escape and play upon the journals when the latter are slightly heated and to subsequently permit the escape of a large quantity of air and cause the air brakes to 95 be applied when the journals become hot.

4. The combination with a railway car including its truck and air-brake system, of a transverse pipe extending across the truck, a flexible pipe establishing communication between the transverse pipe and the air-brake pipe, branch pipes leading from the ends of the transverse pipe to the journal boxes of the truck, fuse caps arranged 100 within the journal boxes and fitted upon 105 the ends of the branch pipes, said fuse caps being each provided with a small aperture and a large aperture, and fuses closing the apertures, the fuse for the small aperture being of a composition which will melt at 110 a lower temperature than that of the large aperture, so that if the journal is only slightly heated the small aperture will be opened, while if the journal is hot the large 115 aperture will also be opened, thereby exhausting the air from the air-brake system and causing the air brakes to be applied, the escaping air in either instance serving to cool the journal.

5. The combination of a journal box, an 120 air pipe leading to the journal box and in communication with a source of compressed air, a fuse cap arranged within the journal box and applied to the end of the air pipe, said fuse cap being provided with a small 125 aperture and a large aperture, and fuses closing the apertures, the fuse for the small aperture being of a composition that will

melt at a lower temperature than that of the large aperture, so that if the journal is slightly heated the small aperture will be opened, while if the journal is hot the large aperture will also be opened, the escaping air in either instance serving to cool the journal.

In testimony whereof I have signed my name to this specification in the presence of two subscribing witnesses.

PAUL J. MURRAY.
